J. M. SUAREZ

ARTICULATED CAR JOINT

Filed Dec. 4, 1925

*Inventor,
J.M. Suarez.
Attorney, Sterling & Buck.*

UNITED STATES PATENT OFFICE.

JOSEPH M. SUAREZ, OF BALTIMORE, MARYLAND, ASSIGNOR OF ONE-TENTH TO
STERLING P. BUCK, OF BALTIMORE, MARYLAND.

ARTICULATED CAR JOINT.

Application filed December 4, 1925. Serial No. 73,223.

To all whom it may concern:

Be it known that I, JOSEPH M. SUAREZ, a citizen of the United States, residing at Baltimore, in the State of Maryland, have 5 invented certain new and useful Improvements in Articulated Car Joints, of which the following is a specification.

This invention relates to articulated railway cars, and particularly to an improved 10 articulated car-joint.

Some of the objects of this invention are as follows:

To provide an improved car-joint which embodies the maximum of safety, flexibility, 15 durability, adjustability, and convenience in assembling, with a comparatively slight cost of manufacturing and maintaining; also to provide a car-joint of this character that permits of a considerable vertical movement 20 of the car-sections with respect to one another and with respect to their common supporting truck on which the intermediate joint-member is secured; also to provide a car-joint of this character which has an exceedingly 25 convenient and effective lubricating means.

Other objects and important features are pointed out or implied in the following details of description, in connection with the 30 accompanying drawings in which:

Fig. 1 is a top plan view of my improved car-joint.

Fig. 2 is a side elevation, the adjoining parts of the car-sections and common truck being shown in vertical section.

Fig. 3 is a vertical sectional view taken in the plane and viewed in the direction indicated by the line 3—3 of Fig. 1.

Fig. 4 is a sectional view in the same 40 plane as Fig. 3, but viewed in the direction indicated by the line 4—4 of Fig. 2.

Referring to these drawings in detail, in which similar reference characters refer to similar parts throughout the several views, 45 and in which a T-beam truck-bolster is shown at T, and in which two channel beams or car-section-ends are shown at C, it is seen that the intermediate joint-member is formed of two separable but securely united 50 socket-elements, viz, an upper socket-element 1 and a lower socket-element 2, and that each of these elements has approxi-

mately hemispherical cavities or sockets therein, as indicated at 3 and 4, respectively. They are not entirely hemispherical, however, because the metal (iron or steel) is omitted at one side of the wall of each cavity, as seen at 5 and 6, respectively. One cavity 3 is complementary to a subjacent cavity 4, and the other cavity 3 is complementary to the other cavity 4; and these pairs of complementary cavities combine to form approximately spherical sockets each having an outlet formed by the complementary recesses 5 and 6. Each outlet 5—6 is oblong in the horizontal direction, as shown in Figures 1 and 3, that is, in the direction laterally of the path of traveling movement of the car. The members 3 and 4 are each provided with apertured horizontal securing flanges 7 and 8, respectively, through which are extended any appropriate and proper number of securing members 9 which may be either bolts or rivets. The lower and upper surfaces of the respective elements or bodies 3 and 4 are preferably plane and horizontal and separated by one or more gaskets 10 which are intended to be removed, one at a time, for compensating for wear of their walls and of the balls 11 that are seated therein. The upper member 1 is formed with oil-ducts 12 which extend to the inner sides of the cavities 3 from any suitable lubricating device indicated at 13. The member 2 includes a channel-plate 14 having parallel flanges 15 that extend down against the opposite edges of the truck-bolster T and cooperate with fasteners 16, which may be either bolts or rivets, for securely and safely uniting the member 2 with the truck-bolster. It will be seen that this downwardly opening channel of the part 14 is as readily applicable to and securable on a truck-bolster of channel-beam construction or I-beam construction as it is to the T-beam construction. The channel-plate 14 is preferably longer than the distance between the laterally facing edges of the flanges 7 and 8, so it has a relatively large area of bearing surface where it is seated on the truck-bolster.

Each ball 11 is part of a connecting member having a neck 17 which is of less extent in its vertical cross section than the vertical

distance across the outlet 5-6, and is of much less extent in its horizontal direction than is the horizontal distance across the said outlet; so, as the ball 11 of each connecting member has rotary movement in the cooperating socket, ample clearance is provided to permit the neck 17 to swing in every direction, thereby compensating for vertical and horizontal curvatures of the 10 track on which the articulated car travels. Each coupling member or connecting member also includes an elongated flanged plate 18 from which the neck 17 tapers towards and to the ball 11. The part 18, of each connecting member, has its upright intermediate part apertured to receive securing means such as bolts or rivets 19 which also extend through the adjoining channel beam or car-frame-member C. Each securing 20 plate 18 has a channel whose edges are formed by parallel flanges 20 and 21, the latter being apertured to receive securing members 19^a which also extend through the lower flange of the adjoining channel-beam or flanged structural car-frame-member. Each connecting member also includes strengthening ribs or flanges 22 that extend from the neck 17 to the top and bottom of the respective flanges 20 and 21, and horizontal stiffening flanges that extend from said neck to the ends of the securing plate 18. The bolt-holes or rivet-holes are through parts of the plate on opposite sides of the stiffening ribs or flanges 22 and 23, so these 30 connecting members are not only exceedingly strong, but comparatively light and inexpensive, also easy to secure in place, in view of the flanges 20 and 21 embracing the structural beams C therebetween while 40 marking these beams for their rivet-holes, or while boring such holes and using the plate 18 as a templet.

I do not intend to limit my patent protection to the exact construction and arrangement here shown, for the inventive ideas include numerous modifications within the scope of the subject matter claimed.

What I claim as my invention is:

1. An articulated car-joint comprising 50 two members each formed with a neck having a ball on one end and means on its other end to secure it to an end of a car-section in such relation that these two members extend towards one another when secured on opposing ends of car-sections, and an intermediate joint-member including two ball-sockets each having an outlet in its upright side which is farthest from the other ball socket, said necks extending through said 55 outlets while said balls are fitted in said ball-sockets and adapted to have limited rotary movements therein, said joint-member having means to secure it to a truck-bolster.

2. An articulated car-joint comprising 60 two members each formed with a neck hav-

ing a ball at one end and means on its other end to secure it to an end of a car-section in such relation that these two members extend towards one another from the car-sections that they are secured to, and an intermediate joint-member including two ball-sockets having outlets in their upright sides farthest from one another, said necks extending through said outlets and having lateral play therein so the balls can have 70 limited rotary movement in the respective sockets, said intermediate joint-member having a downwardly opening channel to receive and embrace the top of a truck-bolster, means being provided to combine 80 with said channel for securing said joint-member on the truck-bolster.

3. In an articulated car-joint, the combination of a member having approximately hemispherical upwardly opening ball-seats 85 and a downwardly opening channel, the latter adapted to receive and embrace a truck-bolster and provided with means to secure it to a truck-bolster, said channel extending laterally of a geometric line through the 90 centers of said ball-seats, and a member formed with downwardly opening ball-seats which are complementary to the first said ball-seats to form ball sockets, means being provided to secure these members to one 95 another and to adjust the ball-seats with respect to one another, substantially as shown, for the purpose specified.

4. The structure defined by claim 3, the second said member including lubrication-ducts extending from its top to the inner sides of the downwardly opening ball-seats. 100

5. In an element of an articulated car-joint, a member comprising a flanged plate having apertures therethrough to receive 105 fasteners for securing it to an upright face of a car-section's end, one flange of said member extending horizontally from the lower edge of said member and provided with openings to receive fasteners for securing it to a horizontal flange of the car-section's end, said member also including a neck extending from the side opposite to said flange and tapering outwards, and said member also including a ball on the outer 110 end of said neck.

6. In an element of an articulated car-joint, a joint-member including two ball-sockets and being divisible in the horizontal plane through the centers of these ball-sockets and provided with superposed and subjacent flanges at opposite sides of the ball-sockets, these flanges being apertured to receive means to secure them to one another, each ball socket having an outlet that is relatively long in its horizontal direction and relatively narrow in its vertical direction, these ball sockets being adapted to receive 120 balls of members which engage with ends of car-sections, substantially as shown. 125 130

7. In an articulated car-joint, the combination with two flanged end beams of two car-sections, and a truck-bolster, of two ball-carrying members each including an upright plate and a horizontal flange, the latter extending under the respective lower flanges of said end beams and secured to the latter, respectively, and a supporting member on said truck-bolster and having two ball-sockets to receive the balls of the ball-carrying members and combine therewith to form two ball-joints. 10
- 5 In testimony whereof I affix my signature.

JOSEPH M. SUAREZ.
